UNITED STATES PATENT OFFICE.

THOMAS MARCUM, OF MUSCOGEE, INDIAN TERRITORY.

BRIDLE.

SPECIFICATION forming part of Letters Patent No. 522,021, dated June 26, 1894.

Application filed July 24, 1893. Serial No. 481,316. (No model.)

To all whom it may concern:

Be it known that I, THOMAS MARCUM, a citizen of the United States, residing at Muscogee, in the Creek Nation and Indian Territory, have invented certain new and useful Improvements in Buggy or Driving Bridles; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention is a new "bridle;" and consists in the novel construction and arrangement of its parts.

In the accompanying drawings: Figure 1 is an illustration showing my bridle in position.

20 Fig. 2 is a perspective view of my bridle.

My invention is described as follows: *a*, is the top band secured to the temple rings *b*, by buckles or sewed strips of leather *c*.

25 *d*, is the brow band secured to the temple rings by being buckled or sewed therein.

e, is the nose piece, the upper end of which is divided into two parts *e'*, and *e''*, and passes up over the horse's head between its ears, one on each side of its top knot, and then passes 30 under the loop *f*, secured to the top band.

These two parts *e'*, and *e''*, of said front piece extend back and are secured to the saddle *g*, forming the hitch rein or reins *g'*, and is prevented from slipping too far forward by means

35 of the stops *h*, immediately in rear of the loop *f*, or the said straps *e'*, and *e''*, may terminate at the stops *h*. The lower part of said nose

piece is divided into two parts *i*, and *i*, each part being secured to the bit rings *j*, by buckle, snaps or otherwise.

Secured to the temple rings *b*, and extending downward are two straps *k*, having attached to their lower ends swiveled snaps *k'*, which are snapped into the chin ring *l*. In said chin ring is secured a strap *m*, having 45 its lower end divided into two parts *n*, and *n*. On the lower end of these straps *n*, and *n*, is secured swiveled snaps *o*, and *o*.

Having described my invention, what I claim as new, and desire to secure by Letters 50 Patent, is—

A bridle, consisting of the top band *a*, having the loop *f*, and secured to the temple rings *b*; brow band *d*, secured to said temple rings; throat straps *k*, one end secured to said temple 55 rings and the other terminating in snaps *k'*; chin ring *l*, working in said snaps; strap *m*, one end secured to said chin ring, its lower end divided into two parts *n*, and terminating in snaps *o*; said snaps working on bit 60 rings *j*; nose piece *e*, its lower end divided into two parts *i*, and secured to the bit rings *j*; its upper end divided into two parts *e'*, and *e''*, and passing under the loop *f*; and stops *h*, secured on the upper end of said parts 65 *e'*, and *e''*, substantially as shown and described and for the purposes set forth.

In testimony whereof I affix my signature in presence of two witnesses.

THOMAS MARCUM.

Witnesses:

S. B. DAWS,
W. H. KORNEGAY.
